BALL-PROJECTING TOY

Gregory Batkin, New York, N. Y.

Application August 16, 1939, Serial No. 290,344

4 Claims. (Cl. 273—96)

My invention relates to ball projecting toys and has particular reference to spring operated projecting toys.

My invention has for its object to provide a toy which can be used for projecting a light Celluloid ball or a similar article to a more or less considerable distance by the action of a helical spring and a projecting hammer, the latter being adapted to be set in the operative position and locked by a trigger. With this arrangement it is possible to accurately aim the device at a target, releasing the spring at an appropriate moment.

My invention is more fully described in the accompanying specification and drawing in which—

Fig. 1 is a sectional elevational view of my toy shown with the striking member set for action against the tension of a spring and locked by a trigger in this position;

Fig. 2 is a top plan view of the same;

Fig. 3 is an elevational view partly in section of a modified device;

Fig. 4 is a top plan view of the same.

25 My ball projecting toy consists of a board 1 with a handle 2 and provided with a funnel-shaped basket 3 for a ball 4. The basket is shown made of wire, but it can be also made of cardboard or tin in the form of a tapering tube. A hole 5 is provided in the board under the basket for admitting a striking hammer into the basket. A convenient form of the hammer is represented by the foot 6 of a projecting member 7 in the form of a football player. It is 30 pivotally supported on a pin 8 fastened to the board 1 and is loosely fitted in a slot 9. A spiral spring 10 provides the striking force. It is fastened at one end to a hook 11 at the front end of the board, the other end of the spring being 35 fastened to the other foot 12 of the figure 7 at 13.

The foot 12 has also a hook 14 passing through a slot 15 in the board and adapted to be held by a sliding trigger plate 16 pivoted at 17 and having a handle 18; thus holding the figure in the armed position with the spring stretched. By moving the handle 18 off the hook 14, the figure is released and is then forcefully turned by the spring into the position shown in dotted lines in Fig. 1, the foot 6 striking the ball 4 and 40 projecting the same with considerable force. The ball may be directed against a target or straight upward, to be caught in the basket upon its return. Two players can project the ball back and forth toward each other, catching it in 45 their baskets.

A modified arrangement is shown in Figs. 3 and 4, the basket being replaced by a straight tube 19 for projecting arrows 20 or similar articles. The lower end of the arrow is supported by a cup 21 held on a flat spring 22 fastened to the board 23 at 25. A slot 24 is provided in the tube for the spring, limiting the movement of the latter to a point above the highest reach of the foot 6 of the projecting figure 7. The cup 21 can be also used for projecting various odd 10 articles, beans, paper wads, etc.

It is understood that my ball-projecting device may be further modified without departing from the spirit of the invention, as set forth in the appended claims.

I claim as my invention:

1. A ball projecting toy comprising a board with a handle at the rear end, the board having a hole at the front end, a projecting tube extending upward from the board around the hole adapted to hold an article to be projected, a projecting member pivotally supported on the board for moving in a longitudinal slot in the board, a portion of the member being adapted to pass into the tubular member through the hole for projecting the article, a spring adapted to pull the projecting member into the striking position, a hook on the lower portion of the projecting member adapted to pass through a slot in the board, and a locking member adapted to hold the hook at the board with the spring stretched, the locking member being adapted to be manually released for operating the projecting member by the spring.

2. A ball projecting toy comprising a board with a handle at the rear end, the board having a hole at the front end, a projecting tube extending upward from the board around the hole adapted to hold an article to be projected, a projecting member pivotally supported on the board for moving in a longitudinal slot in the board, a portion of the member being adapted to pass into the tubular member through the hole for projecting the article, a spring adapted to pull the projecting member into the striking position, a hook on the lower portion of the projecting member adapted to pass through a slot in the board, and a locking plate rotatively supported on the board and adapted to engage the hook, thereby retaining the figure in the armed position with the spring stretched.

3. A ball projecting toy comprising a board with a handle at the rear end, the board having a hole at the front end, a projecting tube extending upward from the board around the hole,

movable means to support an article to be projected at the bottom of the tube, a projecting member pivotally supported on the board for movement in a slot in the board in a plane transverse to the plane of the board, a portion of the projecting member being adapted to pass into the tubular member and to strike the article supporting means for projecting the article, a spring adapted to operate the projecting member, and means to releasably hold the member in the armed position with the spring stretched.

4. A ball projecting toy comprising a board with a handle at the rear end, the board having a hole at the front end, a projecting tube ex-

tending upward from the board around the hole, a cup-shaped member at the bottom of the tube, a resilient member supporting the cup-shaped member, a projecting member pivotally supported on the board for movement in a slot in the board in a plane transverse to the plane of the board, a portion of the projecting member being adapted to pass into the tubular member and to strike the article supporting means for projecting the article, a spring adapted to operate the projecting member, and means to releasably hold the member in the armed position with the spring stretched.

GREGORY BATKIN.
